(57) **CLAIM**

The ornamental design for a bottom rail bracket assembly, as shown and described.

DESCRIPTION

FIG. 1 is a top perspective view of a bottom rail bracket assembly showing our new design in assembled condition, the assembly being comprised of a bottom rail bracket base and bottom rail bracket flange;

FIG. 2 is a perspective view similar to FIG. 1 showing the bottom rail bracket base, separated from the bottom rail bracket flange and set screw;

FIG. 3 is a front view of the bottom rail bracket base;

FIG. 4 is a left side view of the bottom rail bracket base shown in FIG. 3, the left side being a mirror image thereof;

FIG. 5 is a top view of the bottom rail bracket base;

FIG. 6 is a bottom view of the bottom rail bracket base;

FIG. 7 is a rear view of the bottom rail bracket base;

FIG. 8 is a top view of the bottom rail bracket flange, the bottom view being a mirror image thereof;

FIG. 9 is a front view of the bottom rail bracket flange; and,

FIG. 10 is a rear view of the bottom rail bracket flange. The set screw is shown in dotted line in FIGS. 1 and 2 and forms no part of the claimed design.
